(57) **CLAIM**

The ornamental design for a diving computer, as shown and described.

DESCRIPTION

Figure 1.1 is a front, top perspective view of a diving computer showing the new design;

Figure 1.2 is a front elevation view thereof;

Figure 1.3 is a rear elevation view thereof;

Figure 1.4 is a top plan view thereof;

Figure 1.5 is a bottom plan view thereof;

Figure 1.6 is a left side elevation view thereof;

Figure 1.7 is a right side elevation view thereof;

The broken lines depict portions of the driving computer that form no part of the claimed design.
